UNITED STATES PATENT OFFICE.

PHILIP LANGE, OF PITTSBURG, PENNSYLVANIA, ASSIGNOR TO THE WESTINGHOUSE ELECTRIC COMPANY, OF SAME PLACE.

APPARATUS FOR CONNECTING ALTERNATE-CURRENT DYNAMOS.

SPECIFICATION forming part of Letters Patent No. 383,648, dated May 29, 1888.

Application filed October 1, 1887. Serial No. 251,189. (No model.)

To all whom it may concern:

Be it known that I, PHILIP LANGE, a citizen of the United States, residing in Pittsburg, in the county of Allegheny, in the State of Pennsylvania, have invented certain new and useful Improvements in Apparatus for Connecting Alternate-Current Electric Generators, of which the following is a specification.

The invention relates to an organization of apparatus and circuits for connecting alternate-current electric generators in multiple-arc circuit.

The object of the invention is to provide convenient means whereby the relative phases of the currents delivered by several different alternate-current generators may be readily determined, and devices whereby the machines may be connected together in multiple-arc or parallel circuit at the proper moments.

20 In certain applications for Letters Patent filed by Oliver B. Shallenberger, Serial Nos. 220,909 and 224,523, there are described a method and an apparatus for connecting alternate-current machines in the manner set forth.

25 The present invention involves certain improvements in the construction of the switch-board, so that more than two generators may be connected in multiple arc in a convenient manner by employing a single indicator.

30 In the accompanying drawing there is shown, partly in diagram, an organization of four electric generators delivering alternating currents and a single switch-board and indicating device for the same.

35 Referring to the figure, A', A², A³, and A⁴ represent four alternate-current electric generators of convenient type, and L' L² main-line conductors leading to any desired work-circuit. The generators are capable of being connected 40 in multiple arc with the lines L' and L² or with sections l', l², l³, and l⁴ at will by conductors a' b' a² b², &c., through switches M', M², M³, and M⁴. The sections of the line L' L² may be connected or disconnected by switches N', N², and N³.

45 Thus, when it is desired to feed separate circuits from the different generators, the switches may be opened. In order to insure that any given machine shall be connected with the lines at a moment when the current which it 50 is delivering is such as would combine with

the current being delivered to the lines by another generator and flow in the same direction upon the work-circuit, the indicating device C is employed. This device consists of a primary coil, p, and a secondary coil, s, wound upon a core, c. The terminals of the secondary coil are connected through the filament of an incandescent electric lamp, H. The respective terminals of the primary coil p are connected with a binding-post, B², and one 55 arm, e², of a switch, E. The contact-point e² of this switch is connected with a binding-post, B⁴. The point e² of the arm e² is connected with a binding-post, B³. The binding-post B' is connected with the arm e², and thus 60 the posts B' and B³ may be connected with each other through the switch-arm e². The binding-posts B' and B² are respectively connected by conductors 1 and 2 with the switch-arms s' and s² of a switch, S', carried upon a switch-board, T. The binding-posts B³ and B⁴ are 65 respectively connected with the switch-arms s³ and s⁴ of a switch, S², carried upon the switch-board T. Upon the switch-board T there are eight binding-posts, t' t² t³ t⁴ and v' v² v³ v⁴. 70 The posts t' t² t³ t⁴ are respectively connected by conductors u', u², u³, and u⁴ with the conductors a' a² a³ a⁴, leading from one pole of each of the respective dynamos. The conductors v' v² v³ v⁴ are connected in like manner 75 by conductors w' w² w³ w⁴ with the conductors b', b², b³, and b⁴, leading from the other poles of the respective dynamos. The points t', t², and t³ are connected, respectively, also, with switch-points f' f² f³, applied to the switch-arm 80 s' of the switch S', and the point t⁴ is connected with a switch-point, g⁴, applied to the switch-arm s³ of the switch S². The points f² and f³ are also connected with the switch-points g² and g³, respectively applied to the switch-arm 85 s². The points v', v², and v³ are connected with the switch-points h' h² h³, applied to the switch-arm s² of the switch S², and the point v⁴ is connected with a point, k⁴, applied to the switch-arm s⁴ of the switch S². The points h² and h³ 90 are respectively connected with the points k² and k³ of the switch-arm s⁴.

Supposing that the generators A', A², and A⁴ are already connected with the lines L' and L² in multiple arc, and it is desired to add the 100

generator A³, the operation of the apparatus is as follows: If the switch S' is in the position shown in the drawing, with its arms in contact with the points f' and h', respectively, 5 then the respective poles of the generator A' will be connected with the binding-posts B' and B² of the synchronizing device C. From the post B² the connections may be traced to the arm e² through the primary coil p, thence 10 through the point e⁴ to the binding-post B⁴, thence through the conductor 4 to the switch-arm s⁴, and thence through the point k³ and line w³ to the conductor b³, and thus with the pole of the generator A³ corresponding to the 15 pole of the generator A', which is connected with the post B². The other pole of this generator A³ is connected through conductors a³ and u³ to the point g³, thence through the switch-arm s³ to the binding-post B³, thence through 20 the arm e' to the binding-post B' and through the conductor 1 to the switch arm s', thence through the point f' and conductor u' to the conductor a', leading from the corresponding pole of the generator A'. The circuit of the 25 generator A³ is thus completed through the primary coil of the converter in the indicating device C. If the current thus derived from the generator A³ is such that its phases combine and flow in the same direction with those 30 from the generator A', then the lamp H will burn at its highest brilliancy. If, however, they oppose each other, it will burn at its lowest degree and yield little or no light. This will indicate the relative phases of the two 35 generators and the proper moment at which the generator A³ may be connected into circuit with the lines L' and L² through its switch M³, such moment being when the lamp H is at its minimum brilliancy.

40 For the purpose of connecting the individual generators into circuit, as required in any required combination, the switch-board T suffices, for by means of it any two of the series of generators may be connected through 45 the indicating device. Thus in the position shown the generator A³ will be synchronized with the generator A', and vice versa. If the switch S' be moved to the points f² and h², then the generators A² and A³ may be synchronized. 50 If the generators A' and A⁴ are to be synchronized, the switch S' remains in the position shown and the switch S² is moved to the points g⁴ and h⁴; and likewise, by moving the switch S' successively to the points f² and 55 h² and f³ and h³, the generator A⁴ may be synchronized with either the generator A² or A³.

I claim as my invention—

1. The combination, with three or more alternate-current electric generators, of a switch-board for synchronizing the same, consisting 60 of two double-point switches, contact-points for the respective arms of one switch connected with the respective poles of said generators, contact-points for the respective arms of the second switch connected with said poles, 65 and an indicating device included in circuit between the respective switches.

2. The combination, with the alternate-current generators A', A², and A⁴, of the switches S' and S², their contact-points f' f² h' h² g² g⁴ k² k⁴, 70 the indicating device C, connected between the switches, electrical connections from the respective poles of the generator A' with the points f' h', respectively, connections from the respective poles of the generator A⁴ with the 75 points g⁴ and k⁴, respectively, and electrical connections from the respective poles of the generator A² with points f² g² and h² k².

3. A switch-board for connecting different alternate-current generators through an indicating device consisting of two switches, each having two contact-arms and each arm having contact-points, conductors leading from one pole of each generator except one to the respective contact-points of one arm of one 80 switch, conductors leading from the other poles of the same generators to the respective contact-points of the other arm of the same switch, and similar electric connections from the respective poles of all the generators except one of the first-named with the contact-points of the respective arms of the remaining switch.

4. A switch-board for connecting different alternate-current generators through an indicating device consisting of two switches, each having two contact-arms and each arm having contact-points, conductors leading from one pole of each generator to the contact-points of one arm of each switch, conductors 95 leading from the remaining poles to the contact-points of the remaining arms, and an indicating device included in circuit between said switches.

In testimony whereof I have hereunto subscribed my name this 5th day of September, A. D. 1887.

PHILIP LANGE.
